UNITED STATES PATENT OFFICE.

CHARLES ASHOFF, OF PHILADELPHIA, PENNSYLVANIA.

HEDDLE FOR CROSS-WEAVING.

SPECIFICATION forming part of Letters Patent No. 544,497, dated August 13, 1895.

Application filed April 10, 1895. Serial No. 545,179. (No model.)

To all whom it may concern:

Be it known that I, CHARLES ASHOFF, a citizen of the United States, residing in the city and county of Philadelphia, State of Pennsylvania, have invented a new and useful Improvement in Heddles for Cross-Weaving, which improvement is fully set forth in the following specification and accompanying drawings.

- 10 My invention consists of a novel construction of heddle, which is formed by bending a thin flat strip of suitable material so that an elongated loop is formed, a suitable block or spacing device being secured in the upper portion 15 of said loop, whereby a very large eye in proportion to the small amount of metal employed is obtained, the lower extremities of said loop being caused to be in substantial contact with each other for a great portion of 20 their length below said block, whereby a heddle of great resiliency is obtained and economy of space is gained at the point where it is most needed, all as will be hereinafter set forth.
- 25 Figure 1 represents a perspective view of a thin strip of metal adapted to form a heddle embodying my invention. Fig. 2 represents a spacing-block employed in the formation of the eye to be hereinafter referred to. Fig. 3 30 represents a heddle in the process of manufacture, and Fig. 4 represents a finished heddle.

Similar letters of reference indicate corresponding parts in the several figures.

- 35 Referring to the drawings, A designates a thin flat strip of metal or other suitable material, which can be readily bent into the desired shape. The ends B of said strip A are, in the first step of the manufacture of a heddle, bent around toward each other, as seen in dotted lines in Fig. 1, and are temporarily held with the ends B in juxtaposition in any suitable manner. The spacing-block C is now secured, by brazing or otherwise, within the upper portion of the loop, formed by bending the strip A, as described, near the bend, the space between the block and bend forming the eye E, while the limbs B B converge and their extremities are caused to be in substantial contact with each other throughout the greater portion of their length from the spacing-block C, as will be understood from Fig. 4,

which shows the completed heddle D, a thin durable heddle being thus produced which is especially adapted for cross-weaving, and 55 which has a very large eye in proportion to the small amount of metal required in its production, said heddle having also an exterior smooth surface throughout on either side, and I desire to call especial attention to the 60 fact that great resiliency is attained by bringing the extremities or limbs B B of the heddle into substantial contact with each other throughout the greater portion of their length below the spacing-block, and by reason of 65 said resiliency the eye of said heddle, constructed as described, can move freely in one direction or sidewise while it will be less capable of yielding in the opposite directions, in which latter the yarn is passed through the 70 eye, it being further noted that since the lower portion or the free-ends of the heddle constitute the point of attachment of the same in the heddle-frame great economy of space is provided at the point where it is most needed, 75 thereby enabling a large number of heddles to be placed in a very limited space, as is evident, and therefore enabling a great latitude of sidewise movement, which could not otherwise be attained if the completed heddle were 80 left in the shape shown in Fig. 3.

I am aware that it is not broadly new to make a heddle of thin flat material bent into a flat loop, since the general principle thereof is disclosed in the German Patent No. 23,868, 85 dated February 13, 1883, in which is shown a heddle similar to the unfinished article shown in Fig. 3, of uniform width throughout at top and bottom and set in a reed; and I do not, therefore, make any claim to the same, the 90 present invention consisting in bringing the lower limbs or extremities of the heddle together for the greater portion of their length below the spacing-block, as is illustrated in Fig. 4, in which is shown the completed heddle, an article of great resiliency being thus attained and much room being gained at the lower portion thereof, where it is most needed. 95

Having thus described my invention, what I claim as new, and desire to secure by Letters Patent, is—

The herein described heddle, consisting of a flat strip of material A bent into the shape of a loop, and a spacing block brazed or oth-

erwise secured within the said loop, near the bend, the limbs B converging from said block and being brought for a great portion of their length into substantial contact with each other 5 whereby, a heddle of great resiliency and reduced width at the bottom is obtained, the same having an eye of large area in propor-

tion to the amount of metal employed, substantially as described.

CHARLES ASHOFF.
